UNITED STATES PATENT OFFICE

ADELBERT R. SMITH, OF NEWCASTLE, INDIANA, ASSIGNOR TO CHRYSLER CORPORATION,
OF DETROIT, MICHIGAN, A CORPORATION OF DELAWARE

BENDING MACHINE

Application filed May 29, 1930. Serial No. 457,262.

This invention relates to a machine for bending angle bars of T-shape cross section.

The main objects of this invention are to provide an improved machine particularly suitable for bending short lengths of bars which are angle shaped in cross section; to provide a machine which will bend a straight piece of T-shaped stock into semi-circular form; to provide a machine in which relatively short lengths of angle bar stock may be bent throughout the entire length thereof and to provide a machine of simple and substantial construction which will give efficient and satisfactory service and which may be readily adjusted to compensate for wear and use.

An illustrative embodiment of this invention is shown in the accompanying drawings in which:

Fig. 1 is a view in front elevation of my improved bending machine.

Fig. 2 is a view in left end elevation of the same taken from the line 2—2 of Fig. 1.

Fig. 3 is a view in right end elevation as seen from the line 3—3 of Fig. 1.

Fig. 4 is an enlarged sectional view taken on the line 4—4 of Fig. 1.

Fig. 5 is a fragmentary sectional view taken on the line 5—5 of Fig. 4.

Fig. 6 is a fragmentary sectional view taken on the line 6—6 of Fig. 4.

Fig. 7 is a fragmentary sectional view taken on the line 7—7 of Fig. 4.

Fig. 8 is a fragmentary sectional view taken on line 8—8 of Fig. 4.

In the construction shown in the drawings the main frame comprises a base 9 which has a pair of up-standing side frames 10 and 11 bolted or otherwise suitably secured thereon in spaced parallel relation. An electric motor 12 is mounted on the base 9 and the armature shaft 13 thereof is provided with a pinion gear 14 which meshes with a gear 15, keyed to a counter shaft 16 which is journaled at its ends on brackets 17 and 18 which are secured to the base of the main frame. The counter shaft 16 has a pinion 19 keyed thereon, which meshes with a gear wheel 20, keyed to a main shaft 21.

The side frames 10 and 11 are provided with vertically disposed slots extending

downwardly from the top ends thereof, the side edges of which serve as guideways 22 and 23 respectively which embrace boxings 24 and 25 in which the main shaft 21 is journaled. The main shaft 21 carries a main forming roll 26 which consists of a pair of discs of equal diameter held in spaced relation by a relatively thin disc 27 of smaller diameter so that when the three discs are in assembled relation, the roller has a narrow slot 28 in the outer face thereof. The slot 28 is adapted to receive the web flange 29 of a T-shaped bar, the top flanges 30 of which rest upon the outer face of the forming roll, which face is knurled so as to grip the bar when placed thereagainst. At each side of the forming roll 26, the shaft 21 is provided with gear wheels 31 and 32 keyed thereto and spacer sleeves 33 and 34 are interposed between the outer sides of gears 31 and 32 and the adjacent boxings 24 and 25 for holding the roll and gears in rigid position medial of the side frames 10 and 11.

The guideways 22 and 23 also slidably support a pair of boxings 35 and 36 in which is journaled a second shaft 37 in spaced parallel relation above the shaft 21. One end of the shaft 37 protrudes beyond the boxing 35 and side frame 10, and such protruding end has a gear 38 keyed thereto which meshes with a gear 39 keyed on the main shaft 21 between the side frame 10 and the gear wheel 20. Helical compression springs 40 and 41 are provided between the boxings of the main shaft 21 and the boxings for the shaft 37 for normally urging the shaft 37 and its supporting boxings upwardly in their respective guideways.

The top ends of the side frames 10 and 11 are provided with cross head caps 42 and 43 secured thereto which bridge across the upper ends of the vertically disposed slots which form the side frame guideways. The caps 42 and 43, at their medial points, are vertically drilled and threaded to receive set screws 44 and 45 respectively, the lower ends of which bear against the top sides of the boxings 35 and 36 for holding said boxings in adjusted positions against the action of their respective compression springs. Lock nuts 46 and 47 are provided on the set screws 44 and 45.

for securing the set screws in position when adjusted.

The shaft 37 pivotally supports a sub-frame which comprises a pair of frame arms 48 and 49 disposed in spaced parallel relation. The arms 48 and 49 are mounted adjacent one end thereof on the shaft 37 and said arms are generally of arcuate shape. A forming roll 50 is keyed on the shaft 37 in radial alignment with the main forming roll 26 and spacer sleeves 51 and 52 are interposed between the sides of roller 50 and the adjacent sub-frame arms 48 and 49 respectively. The sub-frame arms 48, and 49 project forwardly from their point of pivotal mounting on the shaft 37 and such forwardly projecting ends have a shaft 53 journaled therein which supports an idler roll 54 keyed thereon.

The oppositely extending portions of the sub-frame arms 48 and 49 have shafts 55, 56 and 57 journaled thereon in spaced parallel relation which have forming rollers 58, 59, and 60 respectively keyed thereto. The disposition of the forming rollers carried by the sub-frame and shaft 37 is such that said rollers are spaced angularly with respect to the axis of the main shaft 21, and closely adjacent to the outer periphery of the main forming roll 26.

30 The roll 58, as shown in Fig. 6 of the drawings, is provided at one end thereof with a gear 61 which meshes with the driving gear 32 keyed on main shaft 21. The medial part of the face of the roll 58 has an annular row 35 of shallow depressions 62 formed therein which aids said roll in gripping and turning down the forward end of the angle bar which is to be bent in said machine.

40 The forming roll 59 as shown in Fig. 7 of the drawings is provided at the end opposite to the gear 61 of roll 58, with a gear 63 which meshes with the drive gear 31 keyed on main shaft 21.

45 The forming roll 60 as shown in Fig. 8 of the drawings is provided at the end thereof opposite to the gear 63 of roll 59, with a gear 64 which meshes with the driving gear 32. The foregoing staggered disposition of the driving gears for the rollers 58, 59 and 60 permits these forming rolls to be closely spaced together without the gears interfering with each other.

55 The depending free ends of the sub-frame arms 48 and 49 are secured to a tie bar 65 by cap screws 66 and 67 which rigidly hold the ends of the arms in definitely spaced parallel relation. The bar 65 extends horizontally across the rear end of the machine in overlapping relation to the side frames 10 and 11. The overlapping extreme ends of the bar 65 are drilled to slidably receive studs 68 and 69 which are threaded into the side frames 10 and 11. The stud 68 is provided with lock nuts 70 and 71 which embrace opposite sides of the bar 65. The stud 69 is also provided with lock

70 nuts 72 and 73 which likewise embrace opposite sides of the tie bar 65. Adjustment of the free ends of the sub-frame relatively to the main shaft 21 is secured by suitably positioning the lock nuts 70, 71, 72 and 73 on their respective studs.

75 The side frames 10 and 11 near their top ends are secured together by a pair of tie bars 74 and 75 which are arranged in spaced parallel relation and which have their respective ends secured in said side frames.

80 The front side of the machine is provided with a horizontally disposed table member 76 in the form of an angle bar which has its opposite ends secured to the side frames 10 and 11. The upper side of the table 76 at its medial point is provided with spaced guide blocks 77 and 78 secured by angle clips 79 and 80 respectively upon which the work to be passed into the machine is placed.

85 The rear side of the depending flange of the table 76 has an angle clip 81 secured thereto, the outwardly extending flange of which is positioned in the peripheral slot 28 of the main forming roll 26 so as to be in position to knock out the angle bar which has been passed through the machine and suitably curved thereby.

90 A forwardly inclined chute 82 is provided 95 between the side frames 10 and 11 and directly beneath the forming roll 26 for receiving the pieces of work as they are knocked out of the main forming roll by the clip 81.

95 In the operation of this machine the length of T-bar stock which is to be bent into semi-circular shape is placed upon the guide blocks 77 and 78 with the web portion 29 of the T-bar 100 in the slot between the blocks. The bar is then pushed forwardly underneath the rollers 54 and 50 which are adjusted so as to tightly grip the laterally extending flanges 30 of the T-bar by the roller 50 and the main forming roller 26.

105 The outer face of the main forming roll 26, being knurled, bites into the under side of the flanges 30 and feeds the piece of stock into the machine until the front end thereof strikes the forming roller 58. The forming roll 58 engages the incoming end of the bar and bends the same 110 downwardly, the bar being held against lateral deflection by reason of the web 29 being embraced snugly in the slot 28 of the main forming roll. The shallow depressions 62 on the forming roll 58 aid in gripping and securing the T-bar during its bending operation. As the T-bar continues through the machine it engages the rolls 59 and 60 and is thus bent 115 throughout its entire length.

120 The web 29, by reason of its snug fit in slot 28 causes the formed piece of stock to remain on the main forming roll after it has passed the last roll 60 and continues around until it strikes against the flange of the angle clip 81 at which time the piece of T-bar is 125 130

knocked out of the main forming roll and drops down onto the forwardly inclined chute 82 from which it is discharged out of the front side of the machine.

- 5 The shaft 37 may be vertically adjusted with respect to the main shaft 21 by means of the set screws 44 and 45 so as to compensate for slight variation in the thickness of the stock and for wear in the machine. The rolls 10 58, 59 and 60 may be adjusted with respect to their distances from the main shaft 21 by means of the threaded studs 68 and 69 and lock nuts carried thereby, the entire sub-frame being swingable by movement of the 15 tie bar 65.

Although but one specific embodiment of this invention has been herein shown and described, it will be understood that numerous details of the construction shown may be altered or omitted without departing from the spirit of this invention as defined by the following claims.

I claim:

1. A bending machine comprising a main 25 frame, a main shaft journaled on said frame, a forming roll on said main shaft, a second shaft journaled on said frame in spaced parallel relation to said main shaft, a sub-frame pivotally mounted on said second shaft, a plurality of forming rolls journaled on said sub-frame for cooperating with said first mentioned main shaft roll and means for driving some of said rolls to feed work through said machine.

- 35 2. A bending machine comprising a main frame, a forming roll journaled on said frame, a sub-frame shiftable and rotatable on said main frame, a plurality of forming rolls journaled on said sub-frame and angularly spaced adjacent the periphery of said first mentioned roll and means for moving said sub-frame into and holding the latter in selected positions for predetermining the relation of the rolls of said sub-frame and said 45 main roll.

3. A bending machine comprising a main frame, a main shaft journaled on said frame, a second shaft journaled on said frame in spaced parallel relation to said main shaft, 50 an arcuate sub-frame pivotally mounted adjacent one end thereof, on said second shaft, means for adjusting said second shaft relatively to said main shaft, means for adjusting the free end of said sub-frame relatively to said main shaft, a forming roll on said main shaft, a plurality of forming rolls on said sub-frame for cooperating with said main shaft roll and means for rotating some of said rolls to feed work through said machine.

4. A bending machine comprising a main frame having a pair of up-standing side frames disposed in spaced parallel relation, a main shaft journaled on said side frames, 55 guideways on said side frames, boxings slid-

able on said guideways, a second shaft journaled in said boxings, means for adjusting the boxings of said second shaft relatively to said main shaft, a sub-frame comprising a pair of frame arms disposed in spaced parallel relation, said frame arms being pivoted adjacent one end thereof on said second shaft, a main forming roll on said main shaft, a plurality of forming rolls disposed between said arms for cooperating with said main roll and a gear train connecting said main shaft, second shaft and sub-frame rolls for driving said rolls to feed work through said machine.

5. A bending machine comprising a main frame, a main shaft journaled on said main frame, a main forming roll on said main shaft, a second shaft journaled on said frame above said main shaft, a forming roll on said second shaft in radial alignment with said main roll, means for moving said second shaft toward and away from said main shaft, a sub-frame pivotally mounted on said second shaft, a plurality of forming rolls journaled on said sub-frame in radial alignment with said roll, said sub-frame being pivoted adjacent one end thereof, a tie bar on the free end of said sub-frame, means for securing said tie bar to said main frame in adjusted positions and means for driving said forming rolls to feed work through said machine.

6. A bending machine comprising a main frame, a main shaft journaled on said main frame, a main forming roll secured on said main shaft, a pair of drive gears secured on said main shaft, one at each side of said main roll, a second shaft journaled on said main frame in spaced parallel relation to said main shaft, a sub-frame carried by said second shaft, a plurality of forming rolls journaled on said sub-frame adjacent the periphery of said main roll, a gear on each of said sub-frame rolls, one of said sub-frame roll gears meshing with one of said main shaft driving gears and another of said sub-frame roll gears meshing with the other said main shaft driving gears and means for driving said main shaft.

7. A bending machine comprising a main frame, a main shaft journaled on said main frame, a main forming roll secured on said main shaft, a pair of drive gears secured on said main shaft, one at each side of said main roll, a second shaft journaled on said main frame in spaced parallel relation to said main shaft, a forming roll on said second shaft, a sub-frame carried by said second shaft, a plurality of forming rolls journaled on said sub-frame adjacent the periphery of said main roll, a gear on each of said sub-frame rolls, one of said sub-frame roll gears meshing with one of said main shaft drive gears and another of said sub-frame roll gears meshing with the other of said main shaft driving gears, a pair of intermeshing gears, one on said main shaft and the other on said second

shaft and means for driving said main shaft.

8. A bending machine comprising a main frame, a main shaft journaled on said main frame, a main forming roll secured on said main shaft, a pair of drive gears secured on said main shaft, one at each side of said main roll, a second shaft journaled on said main frame in spaced parallel relation to said main shaft, a forming roll on said second shaft, a sub-frame carried by said second shaft, a plurality of forming rolls journaled on said sub-frame adjacent the periphery of said main roll, a gear on each of said sub-frame rolls, one of said sub-frame roll gears meshing with one of said main shaft drive gears and another of said sub-frame roll gears meshing with the other of said main shaft driving gears, a pair of intermeshing gears, one on said main shaft and the other on said second shaft and means for adjusting said second shaft and sub-frame relatively to said main forming roll.

9. A bending machine comprising a frame, a main forming roll journaled on said frame, said roll having a radially extending slot in the face thereof for receiving the web of an angle bar, a shiftable unit having a plurality of forming rolls journaled in angularly spaced relation adjacent the periphery of and for cooperating with said main forming roll, means yieldably urging said unit away from said main forming roll and means for driving some of said rolls to feed work through said machine.

10. A bending machine comprising a frame, a main forming roll journaled on said frame, said roll having a medially disposed radially extending slot in the face thereof for receiving the web of a T-bar, a tilttable unit journaled on said frame having a plurality of forming rolls located in angularly spaced relation adjacent the periphery of and for cooperating with said main forming roll, said plurality of forming rolls extending axially on each side of said slot for bearing on both flanges of said T-bar.

11. In a machine for bending metal sections, the combination of a pair of related rolls, a mounting swingable about the axis of one of said related rolls, a series of cooperating rolls carried by said mounting and disposed about the axis of said other related roll, means for driving one of said related rolls, and a guide for supporting each section while it is fed to said rolls.

12. In a machine for bending metal sections, the combination of a pair of related rolls, a mounting swingable about the axis of one of said related rolls, a series of cooperating rolls carried by said mounting and disposed about the axis of said other related roll, means for driving said latter related roll and one of said cooperating rolls, and a guide for supporting each section while it is fed to said rolls.

13. In a machine for bending metal sections, the combination with a frame, of a guiding roll, a series of cooperating rolls disposed about the axis of said guiding roll, means for driving said guiding roll, and a support movably mounted on said frame and provided on one side with devices which serve as a guide for each section while it is fed to said rolls and provided on its other side with a stop to arrest the sections after passing between said rolls.

14. In a machine for bending metal sections, the combination of a pair of related rolls, a series of cooperating rolls disposed about the axis of one of said related rolls, means for driving said related rolls, a guide for supporting each section while it is fed to said rolls, and a roll in front of said related rolls and in opposed relation to said guide and cooperating therewith to guide each section to said related rolls.

15. In a machine for bending metal sections, the combination of a guiding roll, a series of cooperating rolls disposed about the axis of said guiding roll, means for driving one of said rolls, a guide for supporting each section while it is fed to said rolls, and means carried by said guide arranged to be engaged by each blank as it completes its pass through said rolls and arrest it and guide it to a receiver.

16. In a machine for bending metal sections, the combination of a pair of related rolls, a mounting swingable about the axis of one of said related rolls, a series of cooperating rolls carried by said mounting and disposed about the axis of said other related roll, means for driving said other related roll and one of said cooperating rolls, and a guide for supporting each section while it is fed to said rolls, the shaft for the driven cooperating roll being geared to the shaft of the driven related roll.

17. In a machine for bending metal sections, the combination of a support, a guiding roll rotatably mounted thereon, a separate roll rotatably mounted on said support in opposed relation to said guiding roll, a series of rolls disposed substantially in an arc about the axis of said guiding roll and cooperating with it and said separate roll for bending metal sections, a pair of spaced members swingable about the axis of said separate roll and supporting said series of rolls for unitary adjustment about said axis relative to said guiding roll, and a guide for supporting each section while it is fed to said rolls.

18. In a machine of the class described, the combination of a support, a guiding roll rotatably mounted thereon, a separate roll rotatably mounted on said support in opposed relation to said guiding roll, a pair of spaced supporting members mounted at one end on the shaft of said separate roll, a series of rolls

5 rotatably supported between said members substantially in an arc about the axis of said guiding roll and cooperating with said guiding and separate rolls to bend metal sections, and means for rigidly supporting the opposite ends of said members.

19. In a machine of the class described, the combination of a support, a guiding roll rotatably mounted thereon, means for driving said roll, a separate roll rotatably mounted on said support in opposed relation to said guiding roll, a pair of spaced supporting members pivotally mounted at one end to swing about the axis of said separate roll, and a series of rolls rotatably supported between said members substantially in an arc about the axis of said guiding roll and cooperating therewith and said separate roll to bend metal sections.

20. 20. In a machine of the class described, the combination of a support, a guiding roll rotatably mounted thereon, a gear fixed to the shaft of said guiding roll, a separate roll rotatably mounted on said support in opposed relation to said guiding roll, a pair of spaced supporting members pivotally mounted at one end to swing about the axis of said separate roll, a series of rolls rotatably supported between said members substantially in an arc about the axis of said guiding roll and cooperating therewith and said separate roll to bend metal sections, a gear fixed to the shaft of one of said rolls and meshing with the gear fixed to the shaft of said guiding roll, and means for driving the guiding roll shaft.

21. In a machine of the class described, the combination of a support, a guiding roll rotatably mounted thereon, a separate roll rotatably mounted on said support in opposed relation to said guiding roll, a pair of spaced supporting members pivotally mounted at one end to swing about the axis of said separate roll, a series of rolls rotatably supported between said members substantially in an arc about the axis of said guiding roll and cooperating therewith and said separate roll to bend metal sections, gearing between the shaft of each of said series of rolls and the shaft of said guiding roll, and means for driving the guiding roll shaft.

22. In a machine of the class described, the combination of a support, a guiding roll rotatably mounted thereon, gears fixed to the shaft of said guiding roll, a separate roll rotatably mounted on said support in opposed relation to said guiding roll, a pair of spaced supporting members pivotally mounted at one end to swing about the axis of said separate roll, a series of rolls rotatably supported between said members substantially in an arc about the axis of said guiding roll and cooperating therewith and said separate roll to bend metal sections, a gear fixed to the shaft of each of said series of rolls

and meshing with one of the gears fixed to the shaft of said guiding roll, said gears on the shafts of the series of rolls being alternately arranged on opposite sides of the adjacent rolls, and means for driving the guiding roll shaft.

23. In a machine of the class described, the combination of a support, a guiding roll rotatably mounted thereon, a separate roll rotatably mounted on said support, and a series of rolls disposed substantially in an arc about the axis of said guiding roll and cooperating therewith and said separate roll to bend metal sections, and a pair of opposed devices arranged forward of said guiding and separate rolls for supporting and engaging a blank while it is being fed to said rolls, one of said devices consisting of a loosely mounted roll disposed between the inner portion of the other device and said separate roll.
